UNITED STATES PATENT OFFICE.

JAMES T. MURPHY, OF CHICAGO, ILLINOIS, ASSIGNOR OF ONE-HALF TO JAMES L. CAREY, OF CHICAGO, ILLINOIS.

SHOWER PIPE.

Application filed October 23, 1922. Serial No. 596,271.

To all whom it may concern:

Be it known that I, JAMES T. MURPHY, a citizen of the United States, and resident of Chicago, in the county of Cook and State 5 of Illinois, have invented a certain new and useful Improvement in Shower Pipes, of which the following is a full, clear, concise, and exact description, reference being had to the accompanying drawings, forming a 10 part of this specification.

Various kinds of paper making machinery embody shower pipes for cleaning felts, rolls, strainer drums, drum molds, etc. These strainer pipes comprise among other 15 things a pipe having a plurality of comparatively small openings through which water or steam is discharged upon the element to be cleaned. These openings frequently become clogged with dirt of various kinds and 20 particularly is this true where the same water is used over and over again. Many means have heretofore been proposed for cleaning these openings and one of the objects of my invention is to simplify the 25 means for cleaning the openings of shower pipes and the operation of cleaning them.

Another object of my invention is to provide means whereby these openings may be cleaned and the dirt dislodged therefrom 30 flushed from one end of the pipe so as not to be discharged upon the element which is supplied with water from the shower pipe.

A further object of my invention is to 35 provide means for supplying hot water under pressure to the shower pipe for cleaning purposes. This is particularly desirable where the water used in the shower pipe carries paraffin or other soluble matter in solution or suspension. Such materials are 40 very difficult to dislodge from a shower pipe, but by supplying hot water thereto, they can be dissolved or melted and carried away.

A still further object of my invention is 45 to provide means for supplying steam under pressure to the shower pipe and means for insuring this steam passing out through the openings of the shower pipe so that the shower pipe can be used for cleaning drum molds, etc.

50 A final object of my invention is to provide a shower pipe of the type referred to which is simple in construction, easy to operate and economical to manufacture.

55 Other objects of my invention will appear as this description progresses, reference

being had to the accompanying drawings, in which

Figure 1 is a plan view of my improved shower pipe;

Figure 2 is a side elevation thereof; 60

Figure 3 is a transverse section taken on the line 3—3 of Figure 1; and

Figure 4 is an enlarged sectional detail taken on line 4—4 of Figure 1.

Throughout the several views similar reference characters will be used for referring to similar parts, and the sections are taken looking in the direction of the small arrows.

Referring to the drawings, my improved shower pipe comprises a pipe 5 having the 70 usual longitudinally spaced openings 6.

Two pipes 7 and 8, respectively, are connected with the inlet end of shower pipe 5 by means of the T union 9. The first of these pipes is designed to supply steam to 75 the shower pipe and the second is designed for supplying water thereto. A valve 10, preferably of the gate type, is inserted in the pipe 7 and a suitable valve 11 provides means for controlling the flow of water 80 through the pipe 8. This valve may be of any suitable construction. The discharge end of the shower pipe is closed by a cap 12 having the valve port 13 formed therein. This port is normally closed by the valve 85 14 which opens inwardly and which is carried by the valve stem 15, which projects outwardly through a bar 16 projecting across the end of the ring 17, which is threaded upon the outer end of the cap 12. A lever 90 18 is mounted upon the ring 17 by means of the link 19 and is joined to the outer end of the valve stem 15, at a point intermediate the ends of the lever 18, by means of a pivot 20. One end of a link 21 is pivotally secured to the free end of the lever 18. The opposite end of the link 21 carries a slotted member 22, the slot of which extends in a direction parallel with the link 21. The handle 10' of the gate valve 10 projects 95 through the slot in the member 22 and may move freely therein for the purpose of operating the steam valve 10 without operating the link 21 of the valve 14, but may be

rigidly connected with the link by the pin 105 23, which can be inserted through registering openings in the bifurcations of the member 22 and the handle 10', as shown in Figure 4. I prefer to secure the pin 22 to the link 21 by means of a flexible cable 24, so 110

that it cannot become lost. Where the shower pipe is comparatively long, I prefer to provide a bracket 25 which is secured to the shower pipe by means of set screws 26, 5 or in any other desired manner, and which is provided with an eye 27 through which the link 21 can slide.

When the shower pipe is in use, the valves 10 and 14 are closed and the valve 11 is 10 open, thus permitting water to enter the shower pipe and be discharged through the openings 6. When it is desired to clean the shower pipe, the handle 10' is secured to the member 22 by means of the pin 23 and then 15 moved to a position to open the valve 10. This movement through the link 21 simultaneously opens the valve 14 and thus permits the steam supplied by the pipe 7 to 20 pass through the shower pipe at high velocity and carry the dirt with it out of the shower pipe. If desired, the valve 11 can at this time be opened to permit water to enter the shower pipe and be mixed with the steam in the $\frac{1}{4}$ union 9 and forced through 25 the shower pipe and out through the valve port 13.

Jets of live steam are frequently used for 30 cleaning drum molds and the like and the shower pipe which I have illustrated herein can be used for that purpose, in which case 35 the valve 11 will be closed, the handle 10' will be disengaged from the member 22, so that the valve 14 can remain in its closed position, while the valve 10 is open. This will permit the desired pipe to be filled with steam under high pressure, and this steam will issue from the opening 6 and impinge upon the drum mold, thus cleaning it.

While I have described the details of construction of the preferred embodiment of 40 my invention, it is to be clearly understood that my invention is not limited to these details, but is capable of other adaptations within the scope of the appended claims.

Having thus described my invention, what 45 I claim is:

1. A shower pipe for paper machinery comprising, a pipe having an inlet and an outlet end, said outlet end having a valve 50 seat formed therein, a valve for coacting

with said seat, said pipe having a plurality of longitudinally spaced openings formed therein, a water pipe and a steam pipe connected with the inlet end of said shower pipe, said pipes being provided with valves 55 for controlling the flow to said shower pipe, and a link detachably connecting said first-named valve and the valve in said steam pipe.

2. A shower pipe for paper machinery 60 comprising, a pipe having an inlet and an outlet end, said outlet end having a valve seat formed therein, a valve for coacting with said seat, said pipe having a plurality of longitudinally spaced openings formed 65 therein, a water pipe and a steam pipe connected with the inlet end of said shower pipe, said pipes being provided with valves for controlling the flow to said shower pipe, and a link connecting said first-named valve 70 and the valve in said steam pipe.

3. A shower pipe for paper machinery comprising, a pipe having an inlet and an outlet end, said outlet end having a valve seat formed therein, a valve for coacting 75 with said seat, said pipe having a plurality of longitudinally spaced openings formed therein, and a water pipe and a steam pipe connected with the inlet end of said shower pipe, said pipes being provided with valves 80 for controlling the flow of said shower pipe.

4. A shower pipe comprising, a pipe having longitudinally spaced openings formed therein, an outlet valve at one end of said pipe, and two inlet valves connected with 85 the other end thereof.

5. In mechanism of the class described, the combination of a shower pipe having a plurality of discharge outlets along its length, a valve for admitting a cleaning fluid to said pipe; a quick-opening valve at one end thereof adapted to provide a relatively large, unobstructed outlet port at this end for the ready discharge of a flushing flow from said pipe in the cleaning thereof, 95 and means for connecting said valves for concurrent operation.

In witness whereof, I hereunto subscribe my name this 18 day of October, 1922.

JAMES T. MURPHY.
